UNITED STATES PATENT OFFICE

JACOB ELLSWORTH GRIFFIN, OF MILWAUKEE, WISCONSIN

DESIGN FOR A RADIOCABINET

Application filed April 26, 1930. Serial No. 35,405. Term of patent 14 years.

to all whom it may concern:

Be it known that I, JACOB ELLSWORTH GRIFFIN, a citizen of the United States, residing at Milwaukee, in the county of Milwaukee and State of Wisconsin, have invented a new, original, and ornamental Design for a Radiocabinet, of which the following is specification, reference being had to the accompanying drawings, forming a part thereof.

The figure is a perspective view of a radio cabinet showing my new design.

The radio cabinet shown is of symmetrical

design and the four corners are of the same general appearance, as are the four sides, except that handles are provided on a pair of opposite sides and a dial panel and hinged cover therefor are applied to the front of the cabinet.

I claim:

The ornamental design for a radio cabinet, substantially as shown and described.

In witness whereof, I hereunto subscribe my name this 19th day of April, 1930.

JACOB ELLSWORTH GRIFFIN.
